UNITED STATES PATENT OFFICE

2,680,632

HEADER CONSTRUCTION

Benjamin Spieth, Racine, Wis., assignor to
 Modine Manufacturing Company, Racine, Wis.,
 a corporation of Wisconsin

Application October 1, 1947, Serial No. 777,335

1 Claim. (Cl. 285—210)

1 This invention relates primarily to heating elements for convection heaters, where economy in the cost of manufacture is of importance. While this disclosure deals primarily with the headers for heating elements of convectors, it will be found that my invention is applicable to other devices as well.

A heating element of the type ordinarily used in convection heaters, have fluid conducting tubes connected to headers, one header arranged to connect with a steam or hot water supply pipe, the other to a return pipe.

Due to the nature of a heating element, it is usually constructed of light gage, and relatively expensive materials, such as copper and brass. Such materials are used due to their great conductivity and also their resistance to corrosion.

The nature of the former headers is such that a complicated part is required to connect all the fluid conducting tubes into the supply pipe. Usually a casting is specified for this duty. But considerable expense is required to mould, cast, clean, inspect, test and machine castings. Furthermore, the walls must be relatively thick to permit the molten metal to flow in a mould without freezing, and to produce a sound casting, and the weight, and dependent cost, is in proportion to the wall thickness. Any casting tends to be brittle and will not withstand as much pressure as parts of the same basic material that have been drawn or rolled. Furthermore, commercially, a certain percentage of castings have porous spots, which result in objectionable leaks. Such leaks must be repaired. In the repairing operation the casting must be heated slowly, and evenly to prevent distortion strains and resultant cracking. When a sufficient temperature is reached the porous area may be brazed. Then the casting must be slowly cooled and retested to make certain that the leak has been stopped. It is obvious that such an operation is costly.

My invention provides a header fabricated from forged drawn, or rolled stock, which is ordinarily a dense and homogeneous product. For equal strength the walls may be thinner, and since the cost per pound of castings is ordinarily greater, a considerable saving is made.

My invention further adapts itself to production of certain elements from long rods on a "screw machine," where production is high and labor cost at a minimum. Other elements may be produced on punch presses, or "cartridge type" presses or high speed spinning machines, where production rates are high. And lastly the assembly of the header may be made on an auto-

2

matically heated, conveyor type of brazing machine, with close control and regulation.

Since the parts may be made of cylindrical form which mechanically is the most desirable form for pressures, an assembly of sufficient strength to resist the pressures ordinarily encountered in heating systems, can be made of relatively light gage materials.

Another object of the invention is to provide a header construction that may be installed with either side up.

Another object is to provide a header body produced from a rod in part and preferably of an octagonal form so that it may be held by a mechanic's wrench.

Another object is to provide sub-headers that project in diametrically opposite directions from the header body and are adapted to be connected with fluid conducting tubes.

Another object is to provide a header construction that may be connected to fluid conducting tubes without the necessity of providing elbows or elbow bends.

With these and other objects and advantages in view this invention consists in the several novel features hereinafter fully described and more particularly defined in the appended claim.

The invention is clearly illustrated in the drawings accompanying this specification in which: Fig. 1 is a view partly in plan and partly in horizontal section of a header construction embodying a simple form of the present invention and showing its application to fragments of a convection heating unit;

Fig. 2 is a view partly in side elevation and partly in vertical section taken along the line 2—2 of Fig. 1;

Fig. 3 is a central vertical longitudinal section taken along the line 3—3 of Fig. 1;

Fig. 4 is a side elevation partly broken out illustrating a slightly modified form of a header construction;

Fig. 5 is a view partly in under plan and partly in section of the header construction seen in Fig. 4;

Fig. 6 is a vertical cross section taken on the line 6—6 of Fig. 4;

Fig. 7 is a side elevation of the sub-headers shown in Fig. 4 but illustrating the same upon a greatly reduced scale; and

Fig. 8 is a side elevation of a second modified form of sub-header on a reduced scale.

Referring to said drawings and first to Figs. 1 to 3 inclusive, the reference character 8 designates the header body of the present header con-

struction, which header body, if desired, may be of octagonal form as seen in Figs. 1 and 2. Extending up part way through the header body is an axial bore 9, the walls of which are threaded as seen at 10 for the reception of a fluid conducting pipe 11. Extending transversely of the header body adjacent its upper end is a stepped bore 12 which intersects the bore 9.

Secured in the transverse bore are tubular extensions 13 which provide sub-headers for the header construction; the ends 14 of the tubular extensions 13 are closed and in the wall of each tubular extension is an opening 15 from the edge of which extends a flange 16 which as a preference enters the interior of the tubular extension.

These tubular extensions or sub-headers may be formed of sheet metal produced on punch presses or cartridge type presses, or high speed spinning machines.

When used in a heating element, tubes 17 are received in the openings 15 of the sub-headers (see Figs. 1 and 2), and a tube 18 is received in an opening 19 formed in the header body, which opening leads the axial bore 9.

As is customary, heat radiating fins 20 are strung along the tubes and as shown may be brazed to side frame members 21 of a convection heating element, as is more fully shown and described in my application for patent on Heating Element for Convection Heaters, Serial No. 776,363, filed on September 26, 1947, and now U. S. Patent 2,545,561 granted March 20, 1951. A supporting plate 22 is brazed to the side frame members at each end thereof and provides means by which the heating element is supported in a cabinet.

The header at the other end of the convection heater may be of the same construction as the one shown, or it may be of any other suitable type of header construction.

In the modified form of header construction shown in Figs. 4 to 7 inclusive, the header body 23 may be formed substantially like the one shown in Figs. 1, 2, 3, with an axial bore 24, and with a transverse bore 25 intersecting the same.

Extending through the transverse bore 25 is a tubular member 26 closed at both ends 26' and providing two sub-headers 27. At its middle portion the tubular member 26 is formed with a V-shaped opening 28 (see Fig. 7), which establishes communication between the sub-headers and the axial bore in the header body.

The wall of the tubular member 26 at the sides of the header body, is formed with V-shaped openings 29, and brazed or otherwise rigidly secured to the wall of said tubular member, around the openings 29 are adapters 30 which are formed with hollow connections 31 for tubes, which connections extend from channel shaped flanges 32 that are formed on the adapters and partially surround the sub-headers and are brazed thereto. If desired, slots 33 may be formed in the flanges 32 in which bodies of brazing material may be received. The header body 23 is formed with an opening 34 in one side wall and the tubular member 26 and adapters 30 are each formed with a flanged opening 35 for the reception of fluid conducting tubes 36.

In this form of construction there may be three or more fluid conducting tubes arranged in one plane and two or more other fluid conducting tubes arranged in a different plane.

Steam or hot water enters the header body through the supply pipe and flows through the sub-headers to the tubes 17. Steam or hot water

also flows from the header body to the tube 18, although this tube may be omitted if desired. The steam or hot water flows through the tubes to the outlet header, and the condensate discharges therefrom as is well understood.

As illustrated in Fig. 8 of the drawing, a header such as that illustrated in Figs. 1, 2, and 3 may be constructed in a manner similar to the header illustrated in Figs. 4, 5, and 6, in which form of the invention the sub-headers or tubular extensions may be formed from a single piece of material. Thus the member 13a illustrated in Fig. 8 corresponds to the member 26 illustrated in Fig. 7 with the exception that the intermediate connections are eliminated and the member 13a is formed with two openings 15a adapted to receive the fluid conducting tubes 17 illustrated in Figs. 1 and 2. With this construction the member 13a is provided with an opening 13b corresponding to the opening 28 in the member 26 and is inserted in the header body in the same manner as the member 26 in the header body 23. It will be noted that, in either case, the header so formed is provided with a pair of tubular extensions extending outwardly from opposite sides of the header body, which tubular extensions may be formed from either two separate pieces, as illustrated in Figs. 1 to 3 inclusive, or a single piece, as illustrated in Figs. 4 to 7 inclusive and 8. Likewise it will be apparent that the construction illustrated in Figs. 1 and 2 may be utilized in connection with a heating element employing more than three fluid conducting tubes as, for example, by extending the length of the tubular extensions 13 and utilizing the hollow connections 31 for the second and fourth tubes.

It is to be understood that the sub-headers and tubes are brazed to the header, and that the fins are brazed to the tubes and to the side frame members.

From the above it is apparent that I have provided a header construction, capable of being constructed of stock material, free from porous spots, pin holes or other potential leaking places. It is simple in construction and highly efficient in operation. Furthermore, the necessity of using elbows or elbow bends between the tubes and header is entirely eliminated.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

In a convection heater of the type comprising spaced fluid conducting tubes and fin elements mounted thereon in heat exchange relationship, a header construction comprising a relatively heavy solid metal header body having two bores intersecting substantially at right angles, one of which provides a through passage the other being closed at one end and provided with internal threads at the other end for detachably receiving a fluid connection, said other end having a non-circular wrench engaging portion, a pair of similar relatively thin tubular sub-headers extending oppositely outwardly from said header body at the outer termini of said through passage and communicating with the interior of said body and having their inner portions rigidly secured to said body at said termini and their outer ends

closed, each of said sub-headers being provided with a lateral aperture having an inwardly extending tubular flange, said body being provided with an aperture communicating with the said other of said intersecting bores and having its axis offset from and extending parallel to the axes of the inwardly extending tubular flanges of the apertures of said sub-headers, all of said apertures operatively communicating with the interior of said body and being normal to the plane of said bores, and the apertures of said sub-headers and said header being adapted to receive therein for rigid assembly therewith the ends of said fluid conducting tubes.
